FILE DRAWER FACE PANEL

Iwao Miyoshi, Tokyo, Japan, assignor to Kyoeikogyo
Kabushikikaisha, Tokyo, Japan

Filed Feb. 22, 1971, Ser. No. 117,881

Term of patent 14 years

Int. Cl. D6—95

U.S. Cl. D6—192

FIG. 1 is a perspective view of the file drawer face panel embodying my design;

FIG. 2 is a side elevation looking at the right side of the panel of FIG. 1;

FIG. 3 is a left side elevation of the panel;

FIG. 4 is a top plan view;

FIG. 5 is a bottom plan view;

FIG. 6 is an enlarged fragmentary section taken along the line 6—6 of FIG. 1; and

FIG. 7 is another enlarged fragmentary section taken along the line 7—7 of FIG. 1.

The back of the panel is flat.

I claim:

The ornamental design for a file drawer face panel, substantially as shown and described.
